UNITED STATES PATENT OFFICE.

MANFRED MANRODT, OF NEW YORK, N. Y.

DUPLICATING OR COPYING APPARATUS.

Application filed May 26, 1924. Serial No. 715,779.

To all whom it may concern:

Be it known that I, MANFRED MANRODT, a citizen of the United States, residing at New York, in the county of Bronx and State of New York, have invented certain new and useful Improvements in Duplicating or Copying Apparatus, of which the following is a specification.

With duplicating or copying apparatus 10 of the rotary type at present in use for writing circular letters, etc., names, addresses or other particular data varying with each letter cannot be duplicated, but must be printed or written in separately, 15 which not only consumes much time, but also spoils the appearance of the letter.

Neither can the apparatus in its present construction be used for addressing envelopes.

20 The main object of my invention is to provide an attachment, whereby individual stencils with varying texts or data can be made to be automatically picked up and fed into and out of the copying apparatus to 25 supply the missing data on the circulars previously copied on the apparatus, to address envelopes, etc.

Another object is to so construct the attachment that it can be readily applied to 30 any existing rotary type of copying machine.

With these and other objects in view, my invention consists in the combination, arrangement and construction of parts as will be hereinafter duly described and defined in 35 the appended claims.

One embodiment of my invention is illustrated in the accompanying drawing in which Fig. 1 is a vertical section of a copying machine of the rotary type equipped 40 with my new attachment; Fig. 1^a is a section of a detail; Fig. 2 is a front elevation thereof; Fig. 3 is a top plan view thereof with the chute broken off; Fig. 4 is a perspective view of an ink-pad carrier; Fig. 5 is a perspective view of an individual stencil; Figs. 6 and 7 are sectional views of 45 parts of the apparatus similar to Fig. 1 illustrating the operation of my attachment; Fig. 8 is a perspective view of a modified ink-pad and Fig. 9 is a section on line 9—9 of Fig. 8.

The duplicating or copying apparatus of the rotary type substantially comprises a frame *a* in which is rotatively supported a horizontal spindle *b* carrying a hollow drum *c* of which a part of the circumference is

cut away, as at *c'*. Below and located in a vertical plane with the spindle *b* is a second spindle *d* carrying a roller *e*. The opposite longitudinal edges *c²* of the drum at the cutaway part *c'* thereof are bent inwardly and serve for the attachment of an ink-pad *f* over which is placed the usual stencil made of wax paper (not shown). The drum is rotated by means of gears *g*, *h* and a crank 65 handle *i*. The matter to be multiplied or copied is typewritten or printed on the wax paper, which is suitably fastened to the drum over the ink-pad and the sheets to be printed on are fed by hand continuously 70 from a tray *j* by a guide roller *k* into the printing position between roller *e* and stencil and after each operation discharged onto a second tray *l*.

75 Thus far the construction is well known and does not constitute part of this invention.

As my attachment is intended principally for copying names, addresses or the like on letters previously copied by the apparatus, 80 I may, in order to save time, leave the previously used ink sheet intact and put my new ink sheet on top of the former. My new ink sheet, according to the text used, 85 may have its inking surface extend only over a part of the drum, while the other extends over the entire solid part of the drum surface. To prevent soiling the sheets in which the new matter is to be added or the envelopes by the underlying previously used ink-pad; and to enable the fastening 90 of my auxiliary ink-pad, I employ a blanket 95 of sheet metal or the like adapted to fit around the entire printing surface of the drum. This blanket is provided at its ends with hooks or links 11 or the like, which can be turned to extend across the hollow 100 of the drum through the cutaway part *c'* and connected together so as to tightly hold the blanket in position on the printing surface of the drum. The ink-pad 13, which is of a size conforming with the stencil to be used, is fixed to the outer face of said blanket and extends across the same, as best seen in Fig. 2. Near the side edges of said 105 blanket 10 and in alignment with its ink-pad 13, I provide short pins or projections 12, one at each side, the object of which will be hereinafter fully explained.

110 Fixed to the main frame of the machine, is an auxiliary frame composed of front and rear side bars 16, 16' and front and rear

- cross bars 16², 16³ and fixed to the front bars of said auxiliary frame are circularly curved side rails 17 whose diameters are somewhat larger than the total diameter of 5 the drum *c* and blanket 10 mounted thereon to form annular spaces 17' between the blanket and said rails. To the auxiliary frame are also fixed curved rails 18, which extend around and above the upper part of 10 the drum and at their rear ends have attached to them a trough or chute 15 arranged in an inclined position with the lower end directed forwardly and terminating near the rear upper part of the drum. The upper part of the chute is supported on legs 15' and by lateral arms 15² fixed to the main frame. 15
- The stencils, which are adapted to be fed by gravity from the chute 15 into the apparatus, comprise each a comparatively narrow cylindrically curved metal member 14 (Fig. 5) recessed longitudinally, as at 14' and a piece of oil or wax paper 14² containing the matter to be copied and which is fastened to the inner face of the metal sheet 14 over the recess 14', the size of said recess and of said wax paper 14² being made according to the text desired to be copied. At 20 each end, the inner face of the metal sheet 14 or member 14 is formed with a pair of transversely extending lugs or blocks 14³, 14⁴ separated from one another and forming a recess or notch 14⁵ between themselves. The stencils are adapted to be stacked in the 25 chute to rest on one another with their lugs and extend longitudinally of the drum *c*. The chute is formed with side walls 15³ and a bottom 15⁴, the free edges of said side walls being bent over the open front of said chute. 30 The lower ends of the side walls 15³ and the front part of the bottom 15⁴ are cut away, as at 15⁵ and 15⁶, sufficiently to expose the front edge of the lowermost one of the stencils stacked in the chute and one of the lugs 35 at each end thereof. The rear part of the bottom 15⁴ of the chute 15, as seen from Figs. 1 and 1^a, extends away from the drum in a somewhat downwardly inclined position, so that the stencils will be held thereon in a rearwardly and downwardly inclined 40 position and be thereby prevented from falling out through the opening 15⁶ in the bottom of the chute. The forward edge of the lowermost stencil will lie close to the drum and the notches 14⁵ thereof be in the path of the pins or projections 12 of the blanket 10, which pins, when the drum is rotated in the 45 direction of the arrow *x*, will pass into the notches 14⁵, and on engaging the forward lugs 14³ pull said stencil out from the chute through the open parts 15⁵ of the side wall 15³. The stencil will then be lodged on the drum with the ends thereof resting on the end flanges *c*³, *c*⁴ of said drum and leaning with one end against a collar *c*⁵ of the latter 50
- 60
- 65

(Fig. 3). As the drum continues its rotation in the same direction, the stencil 14 passes into the annular spaces 17' between the rails 17 and the blanket 10 and is held by said rails 17 from falling off the drum. 70 The printing or copying is effected in the same manner as with the ordinary stencil at the time the stencil passes over the roller *e*, the roller pressing the recipient such as letter or envelope against the stencil 14² and 75 the latter against the ink-pad 13.

Fixed to the rear edge of the bottom of the chute are one or more downwardly projecting rigid fingers 19, the lower ends of which are made to terminate close to the 80 face of the drum *c* or blanket 10 and lie in the path of the front edge of the stencil 14 engaged by the drum.

When during the rotation of the drum, the stencil arrives close to the said fingers 85 19, the latter will engage the front edge thereof and as the drum continues to revolve, lift the stencil out of engagement with the pins 12 of the blanket. The released stencil will then drop off the drum 90 onto a suitable collecting means, such as a tray 20.

Fixed to the rear of the auxiliary frame at 21', is a shelf-like member or platform 21 extending longitudinally throughout the 95 length of and at the rear of the drum. This platform has a rear wall 21² and sidewalls 21³ and fixed to the latter are rigid posts 22 from the upper ends of which are tiltably suspended by arms 23 rearwardly inclined 100 guide members 24. The forward ends of said members are connected by a cross member 24', which bears with a slight pressure against the drum *c* or the blanket 10, the pressure being exerted by weak springs 25 105 acting on the arms 23. The rear ends of the members 24, which project above the shelf 21, are bent in a downwardly and forwardly inclined position, and have attached to them below said shelf a bar or board 26, 110 which extends immediately above the tray 20. The posts 22 are extended below the bottom of the shelf 21 and are formed with a cross piece 22' extending longitudinally of the drum. This cross piece 22' in conjunction with a second cross piece 27 fixed to the legs 15' of the chute form supports for the removable tray 20. 115

When a stencil, after the printing operation, is released by the rear ends of the bars 17 and arrives at the cross bar 24', it pushes the latter rearwardly against the tension of the springs 25. Thereby the board 26 will be swung rearwardly and will displace the stencil or stencils that may have accumulated on the tray 20. 28 denotes a weighted guide or abutment, which may be movably supported on said tray and which will retain the stencils dropping onto the tray in 125 upstanding position and in order. 130

The mode of operation is as follows:—

When it is desired to insert in copied or printed letters or circulars or on envelopes, names, addresses or other data, the letters, envelopes or other recipients of said printing matter L are stacked on the tray or base J, whence they are adapted to be fed by hand into the machine as usual. The chute is filled with the stencils 14 in a previously arranged order, so as to rest upon one another with the lugs 14^a extending forwardly. After fastening the blanket 10 to the drum c in the aforescribed manner, the latter is rotated by hand. As the pins 12 during the rotation of the drum in the direction of the arrow x arrive below the lowermost stencil, they enter the notches 14^b thereof and on engaging the front lugs 14^a, pull said stencil out from the chute and carry the same along with the drum. The stencil, on passing over the roller e in co-operation with the ink-pad 13, will produce the copying of the printing matter on the letter or envelope that happens to lie between it and the roller e. As the rotation of the drum continues, the stencil rises at the rear of the drum and after its release from the guide rails 17 reaches the fingers 19, which on engaging the front edge of said stencil, lift the latter from the drum, permitting it to slide down onto the guide arms 24 and thence drop off onto the shelf 21 landing thereon on its rear edge, but by its own weight tumbling over forwardly and dropping down onto the tray 20 between the cross piece 26 and the rest 28.

At the starting of the printing or copying operation, the rest 28 is adapted to be close to the board 26, the space between them being smaller than the width of a stencil, so that when a stencil drops onto the tray, it will be retained on its edge leaning with its back against said rest. Each time a stencil rises on the rear of the drum c, it will in passing the arms 24 slightly swing the latter rearwardly in consequence of which the board 26 will shove the stencils accumulating between it and the rest 28 in the same direction making room for a new stencil.

When all stencils have been dropped out from the chute, the tray 20 can be removed and the stencils thereon, which in the aforescribed manner have been arranged in their original order, can be dropped back into the chute for repeated use when desired.

In Figs. 8 and 9, I have shown a modified ink blanket 10^a. The same may be made of fabric with reinforced sheet metal edges 10^b, 10^c and have an ink-pad 13^a adjustably fixed thereto. To this end, a sheet metal plate 10^d is fixed to the metal edges of the blanket to extend transversely thereof. This plate is longitudinally slotted at 10^e.

The ink-pad proper 13^a is fixed by gluing or otherwise to a sheet metal base 10^f, which by stamping is formed with downwardly extending flaps 10^g passing through the slot 10^e and the free ends of which are bent over 70 to engage a second metal plate 10^h. The ends of the blanket are adapted to be hooked together by hook 11^a and eyelet 11^b, after the blanket is mounted around the drum, as the heretofore described blanket 10. By 75 making the ink-pad adjustable, the size of the latter can be made just large enough to cover the printing matter on the stencil.

What I claim is:—

1. In a duplicating or copying apparatus 80 the combination with a rotary drum, of a flexible sheet carrying an ink pad and adapted to be removably mounted on said drum, means on said flexible sheet capable of interlocking with one another to hold the latter in position on said drum, a stack of automatically fed stencils, and means on said flexible sheet arranged in alignment with said ink pad and capable during each revolution of catching and positioning one stencil at a time over said ink pad. 90

2. In a duplicating or copying apparatus 95 the combination with a hollow rotary drum, of a flexible sheet carrying an ink pad and adapted to embrace a part of the circumference of said drum, means projecting from the opposite ends of said flexible sheet and capable of being extended through said drum and of interlocking with one another to removably hold said sheet on said drum, a stack of automatically fed stencils, and means on said flexible sheet in alignment with said ink pad and capable during each revolution of catching and positioning one stencil at a time over said ink pad. 100

3. In a duplicating or copying apparatus, 105 the combination with a rotary drum, of a flexible sheet carrying an ink pad and adapted to be removably mounted on said drum, link members projecting from the opposite ends of said sheet capable of interlocking with one another to hold said sheet in position on said drum, a stack of gravity fed stencils, and means on said flexible sheet in alignment with said ink pad and capable 110 during each revolution of catching and positioning one stencil at a time over said ink pad. 115

4. In a duplicating or copying apparatus, 120 the combination with a rotary drum, of a flexible sheet carrying an ink pad and adapted to be removably mounted on said drum, means projecting from the opposite ends of said sheet capable of interlocking with one another and of holding said sheet in position on said drum, a stack of gravity fed stencils each formed with notches at its ends, and catches projecting from said sheet 125 in alignment with said ink pad and capable during each revolution of engaging the 130

notches of the lowermost stencil of said stack and positioning the same over said ink pad.

5. In a duplicating or copying apparatus, the combination with a rotary member, of a flexible member attached to said rotary member and carrying an ink-pad, a chute, a plurality of stencils stacked in said chute to feed by gravity toward said rotary member, each stencil being formed with notches at its ends, projections on said flexible member in alignment with said ink-pad and capable during each revolution of engaging the notches of the stencil lying lowermost in said chute and projecting into their path and of retaining the same in position over said ink-pad, means for supporting said stencil in position, while in its downward course, automatic means for removing the stencil after completion of its copying operation, means for collecting the stencils dropping off the rotary member and means for automatically restoring said stencils on said collecting means to their initial relative position.

6. In a duplicating or copying apparatus, the combination with a rotary drum, of a flexible sheet carrying an ink pad and adapted to be removably mounted on said drum, means on said sheet capable of interlocking with one another and of removably holding said sheet in operative position, a stack of automatically fed stencils, means projecting

from said sheet in alignment with said ink pad and capable during each revolution of catching and positioning one stencil at a time over said pad and means for automatically removing each stencil from said drum at the completion of its copying operation.

7. In a duplicating or copying apparatus, the combination with a rotary drum, of a flexible sheet carrying an ink pad and adapted to be removably mounted on said drum, means on said sheet capable of interlocking with one another and of removably holding said sheet in operative position, a stack of automatically fed stencils, means projecting from said sheet in alignment with said ink pad and capable during each revolution of catching and positioning one stencil at a time over said pad, means for automatically removing each stencil from said drum at the completion of its copying operation and means for automatically restoring the removed stencils to their initial arrangement.

8. In a duplicating or copying apparatus, the combination with a rotary drum, of a flexible sheet carrying an ink pad and adapted to be removably mounted on said drum, a stack of automatically fed stencils and means on said sheet capable during each revolution of catching and positioning one stencil at a time over the said ink pad.

In testimony whereof I affix my signature.

MANFRED MANRODT.
